UNITED STATES PATENT OFFICE.

ROBERT F. MERCER, OF BROOKLYN, NEW YORK, ASSIGNOR TO THE MERGENTHALER LINOTYPE COMPANY, A CORPORATION OF NEW YORK.

LINOTYPE-MACHINE.

SPECIFICATION forming part of Letters Patent No. 790,447, dated May 23, 1905.

Application filed September 1, 1904. Serial No. 223,079.

To all whom it may concern:

Be it known that I, ROBERT F. MERCER, of Brooklyn, county of Kings, and State of New York, have invented a new and useful Improvement in Linotype-Machines, of which the following is a specification.

This invention has reference to the magazine and distributing mechanism of the Mergenthaler linotype-machine, such as represented in Letters Patent of the United States No. 436,532. In this machine matrices fall from the lower edge of a distributer-bar into curved guiding-channels, through which they descend into the upper end of an inclined magazine. The magazine consists of parallel plates having their opposing faces grooved to receive and guide the upper and lower edges of the matrices. The intermediate channels or guides delivering to the upper ends of the magazine are formed in a hinged frame, technically known as the "channel-entrance." This frame may be turned backward in order to give access to the upper end of the magazine and the adjacent parts of the overlying distributer. It sometimes happens that when the channel-entrance is turned backward a matrix just released or on the point of being released will pass down into the upper end of the magazine and fall upon its side instead of properly entering the guiding-grooves at its edges. These matrices lying on their sides will slide downward into the magazine until arrested by the matrices therein. Their extraction is attended by a loss of time and frequently by disarrangement of other matrices.

The object of my invention is to prevent these falling matrices from passing into the magazine and retain them in such position that they may be easily removed. To this end I provide in the upper end of the magazine between the guiding-grooves—that is to say, between the paths traversed by the upright matrices—a series of vertical pins so located that while they permit the matrices to descend in their proper positions they will arrest the fallen matrices. These guard pins or stops may be made in any suitable form and applied in any suitable manner, the

only requirement being that they shall prevent the matrices which lie on their sides from descending into the body of the magazine. In the drawings I have shown a series of stop-pins secured at their upper ends to a bar, so that they may be thrust downward through a series of holes in the top plate of the magazine. This arrangement admits of their being instantly withdrawn when the interior of the magazine is to be cleaned by a brush, according to the ordinary practice.

Referring to the drawings, Figure 1 represents a vertical cross-section from front to rear through the upper end of the magazine, the channel-entrance, and the distributer with my improvement applied thereto. Fig. 2 is a perspective view of the foregoing parts looking from the rear, the channel-entrance being shown in its open position and all parts shown in section at one end. Fig. 3 is a top plan view of the grooved face of the lower magazine-plate, showing the relation of my stop-pins to the channels which receive the matrices.

Referring to the drawings, A represents the fixed horizontal distributer-bar, with distributer-teeth along its lower edges.

B B represent matrices having their upper ends notched and toothed, so that they are held in suspension by the distributer-bar until they arrive over their appropriate magazine-channels.

C C are the parallel horizontal screws which engage the edges of the matrices for the purpose of carrying them along the distributer-bar.

D represents the channel-entrance, having its upper surface divided by a series of parallel plates d into a series of channels or passages, into which the matrices fall when delivered by the distributer-bar. This channel-entrance is extended downward and forward in a curved line, so that the matrices may be delivered from its lower end directly into the upper ends of the magazine-channels.

E represents the magazine, consisting of the top and bottom plates e and e', spaced a suitable distance apart and provided on their op-

posing faces with the grooves or channels ϵ^2 to receive and guide the upper and lower edges of the descending matrices.

So far as described the parts are of the ordinary construction and arrangement and operate in the ordinary manner.

The channel-entrance stands normally in the position shown in Fig. 1, its upper edge in position to receive the matrices from the bar 5 and its lower edge in position to deliver them into the magazine. Under normal conditions each matrix passing from the channel-entrance D into the magazine will be held and guided at its upper and lower edges, and thus maintained in an upright position, as shown in Fig. 2. When, however, the channel-entrance is swung backward on its hinge or opened, as shown in Fig. 2, a matrix will sometimes fall upon its side and enter the upper end of the 15 magazine, as shown in the middle of the magazine in Fig. 2, its upper and lower edges failing to enter the grooves in the plates. It is to arrest these matrices in the upper end of the magazine and in such position that they 20 may be readily removed that my improvement is designed. In the form shown it consists of a series of upright pins G, secured to a bar g, overlying the magazine and extending thence downward through holes in the top 25 plate to the upper surface of the bottom plate, or practically so. These pins are located at points between the grooves or channels, or, in other words, between the paths pursued by the matrices, so that the matrices standing on 30 edge in the proper position may pass between them without interference. The distance between the pins is such, however, that it is impossible for a matrix lying on its side to pass between them. The fallen matrices 35 are consequently arrested at or near the upper 40

end of the magazine, so that they may be conveniently and instantly removed.

The essence of the invention resides in the employment of uprights or stops in any form which will permit the passage of the upright 45 matrices, but arrest those which have fallen. They may be either removable, as shown, or they may be located permanently in position.

Having described my invention, what I claim is—

1. In a linotype-magazine, comprising a pair of grooved plates to guide the matrices on edge, stops arranged to arrest the fallen matrices.

2. In a magazine for a linotype-machine, the combination of two grooved plates adapted to 55 guide the edges of the matrices, and stops, G, to prevent the passage of the fallen matrices.

3. The combination with a magazine comprising upper and lower grooved plates, a removable bar, g, provided with a series of stop- 60 pins projecting into the magazine to arrest the fallen matrices.

4. In a linotype-magazine having grooves to guide the opposite edges of the matrices, removable stops to arrest the fallen matrices. 65

5. A matrix-stop for application to a linotype-machine, consisting of a bar adapted to extend transversely across the upper end of the magazine, provided with pins of suitable length to project downward into the magazine 70 to the surface of the lower plate, in order to arrest the fallen matrices lying on said plate.

In testimony whereof I hereunto set my hand, this 24th day of August, 1904, in the presence of two attesting witnesses.

ROBERT F. MERCER.
